[57] CLAIM

The ornamental design for a sorting apparatus, substantially as shown.

DESCRIPTION

FIG. 1 is a front elevational view of a sorting apparatus showing my new design;
FIG. 2 is an end elevational view thereof, viewed from the left end of FIG. 1;
FIG. 3 is a rear elevational view thereof;
FIG. 4 is an end elevational view thereof viewed from the right end of FIG. 1;
FIG. 5 is a top plan view thereof; and
FIG. 6 is a bottom plan view thereof.

*FIG. 1.**FIG. 2.**FIG. 3.**FIG. 4.**FIG. 5.**FIG. 6.*
